UNITED STATES PATENT OFFICE

AUGUST E. R. BLOMQUIST, OF CLEVELAND, OHIO

MANICURING DEVICE

Application filed July 21, 1928. Serial No. 294,419.

This invention relates to improvements in the class of manicuring devices disclosed in my copending applications Serial Nos. 136,474 and 252,763, filed, respectively, on the 5 20th day of September, 1926, and the 8th day of February, 1928.

Devices of the class referred to are power driven, and are especially adapted for use in beauty parlors, barber shops and like 10 places; and among the more important objects of the invention are to provide a device of this class that is compact, and is neat and attractive of appearance; that is very convenient of use, and is easy of control; that 15 enables high quality work to be speedily performed; that offers no appreciable resistance to the natural movements and different positions of the operator's hands while performing the manicuring operations thereby to 20 serve the operator's strength and prevent strain and fatigue; and to provide a power operated manicuring device in which the file and buffer are reciprocated in much the same 25 way as the corresponding manual instruments are manipulated.

The foregoing objects, with others herein-after appearing, are attained in the embodiment of the invention illustrated in the accompanying drawings wherein similar reference characters designate corresponding parts throughout the several views.

In the drawings, Fig. 1 is a side elevation of my improved manicuring device; Fig. 2 is a front elevation thereof, the manicuring instrument being omitted and the casing being broken away to reveal the motor; Fig. 3 is a sectional side elevation of the device; Fig. 4 is a fragmentary plan view with the cover of the gear casing removed; Fig. 5 is an enlarged plan view of the forward end of the manicuring instrument; Fig. 6 is a front elevation of the instrument; Figs. 7 and 8 are longitudinal sections, at right angles to each other, of the front portion of the instrument; 40 Figs. 9 and 10 are a front elevation and side

elevation, respectively, of a file for use with the instrument, said views being on a scale somewhat reduced with respect to that of Figs. 5 to 8; and Figs. 11 and 12 are similar views, on the same scale as Figs. 9 and 10, 50 of a buffer for use with the instrument.

The supporting structure or frame of the machine is designated generally by the reference numeral 1 and is in the nature of a hollow casting whose lower end is enlarged to 55 provide a housing 2 for an electric motor 3 shown as supported, with its upper end within an aperture of a web 4 of the housing, by screws that pass through and are sustained by the top wall of said housing.

Supported a suitable distance above the housing 2 by a bracket 8 is a gear case 9 that is circular in plan and is threaded at its upper end for the application of a cover 10. The housing 2, bracket 8 and gear case 9 are preferably integral parts of the casting that constitutes the supporting structure or frame 1.

Connected, as by a coupling 11, to the shaft 12 of the electric motor 3 is a shaft 13, and the upper end of this shaft has secured to it, 70 through a coupling 14, the lower end of a spindle 15 that carries a pinion 16 at its upper end. The spindle 15 is journaled within a bushing 17 that is fitted within a bore in the bottom of the gear case 9 and which bore is surrounded at its lower end by a boss 18 that is in alignment with the boss 19 that rises from the top wall of the housing 2. Supported by and between the bosses 18 and 19 is a sleeve 20 that encases the shaft 13. Within a second bore that is formed in the bottom wall of the gear case 9 and parallels the previously mentioned bore is a bushing 21 within which one terminal, designated 22, of a flexible shaft 23 is journaled, the body portion 75 of said shaft being encased by a sheath 24. A gear 25 is fastened to the terminal 22 and meshes with the pinion 16.

It will be seen from the description thus far that when the motor 3 is energized it will 90

drive, through the shaft 13, spindle 15, pinion 16 and gear 25, the flexible shaft 23. A cable 28 enters one side of the housing 2 and carries wires or conductors 29 and 30 that constitute the circuit through which current is supplied to the motor, the latter wire or conductor including a switch 31 that is accommodated by an offset portion of the housing 2 and involves push buttons 33 that are exposed through openings in the housing.

A lubricant well 35 is formed in the bottom of the gear case 9 between the previously mentioned bores thereof and the same contains a mass or body 36 of suitable absorbent material adapted to be saturated with oil, and from which the oil is conducted by a wick 37 through a transverse bore that is formed in the wall of the gear case and aligned ports in the bushings 17 and 21 to the spindle 15 and terminal 22 of the flexible shaft. An oil hole through which the lubricant is adapted to be supplied to the well 35 is shown at 38 in Fig. 4.

To the free end of the sheath 24 is connected the stock or handle 40 of a manicuring instrument designated generally by the reference numeral 41; and the corresponding end of the flexible shaft 23 that is encased in said sheath is suitably coupled to a mandrel 42 that is journaled in a longitudinal bore of the stock or handle 40 and carries at its forward end a crank disk 43. The forward end of the stock or handle 40 terminates in a generally rectangular head 44 the top of which is formed by a removable cover plate 45 that is held in place by screws 46, and extending transversely through the head 44 is a T-slot within which is guided a slide 47 having a forwardly extended neck 48. The neck 48 is provided with a bore 49, and is split so that said bore may be contracted when the opposed sides of the neck 48 are drawn toward each other by means of a clamp 50, said clamp involving a thumb screw 51. The rear face of the slide 47 has a transverse groove 52 within which a block 53 operates that is carried by a crank pin 54 that extends forwardly from the previously mentioned disk 43, said disk being accommodated by an appropriately shaped recess that is formed in the rear wall of the T-slot wherein the slide 47 operates.

55 (Figs. 1, 9 and 10) is a file, having a shank 56 that is adapted to be inserted within the bore 49 of the slide 47 and secured therein when the neck of said slide is contracted by means of the clamp 50.

A buffer 57 (Figs. 11 and 12) is adapted to be similarly connected through its shank 58 with the slide 47.

In the use of the device, the file 55 is first attached to the instrument 41 and the operator then sets the machine in operation by depressing the appropriate button 33 of the switch 31 to close the circuit to the motor 3.

When the motor is energized it will drive, through the connections above described, the mandrel 42 to rotate the crank disk 53. As said disk rotates it imparts a circular motion to the crank pin 54, and this circular motion of the crank pin is converted into a reciprocating motion in the slide 47 by reason of the driving connection between the crank pin and slide effected through the block 53, that is journaled on the crank pin, and the groove 52 in the rear face of the slide, said block moving back and forth within and longitudinally of said groove in response to the throw of the crank pin in a direction normal to the direction of movement of the slide. This imparts a reciprocating action to the file 55 which may then be engaged with the nail to be operated upon. To perform the polishing operation, the buffer 57 is substituted for the file 55 and the instrument is used as before with the face of the buffer in contact with the surface of the nail. It is evident from the fact that the flexible shaft 23 is suspended from the gear case 9, and is therefore capable of swinging to, fro and about with free universal movement, that no appreciable resistance is offered to the movements of the instrument 41 during the manicuring operations.

Having thus described my invention, what I claim is:

1. In a manicuring device of the class set forth, the combination of a supporting structure incorporating a base, driving mechanism sustained by the structure a suitable distance above the base, a flexible shaft operatively connected to said mechanism and depending substantially vertically therefrom and capable of free swinging movement, and a manicuring instrument carried by the free end of the flexible shaft.

2. In a manicuring device of the class set forth, the combination of a structure incorporating a base, a bracket rising from the base and offset laterally with respect thereto, and a support carried by the bracket and overhanging the base; driving mechanism sustained by the support, a flexible shaft operatively connected to said mechanism and depending therefrom and capable of free swinging movement, and a manicuring instrument carried by the free end of the flexible shaft.

3. In a manicuring device of the class set forth, the combination of a supporting structure incorporating a hollow base and a casing supported by and above the base, driving means within the base, power transmitting mechanism in the casing, driving connections between the driving means and said mechanism, a flexible shaft operatively connected to the power transmitting mechanism and depending from said casing and capable of free swinging movement, and a manicur-

ing instrument carried by the free end of the flexible shaft.

4. In a manicuring device of the class set forth, the combination of a supporting structure incorporating a hollow base, a bracket rising therefrom and offset laterally with respect thereto, and a casing carried by the bracket and overhanging the base, power transmitting mechanism in the casing, driving connections between the driving means and said mechanism, a flexible shaft operatively connected to the power transmitting mechanism and depending from said casing and capable of free swinging movement, and a manicuring instrument carried by the free end of the flexible shaft.

5. In a manicuring device of the class set forth, the combination of a structure incorporating a hollow base, a bracket rising from the base, and a casing carried by the upper end of a bracket and overhanging the base, a motor supported within the base with its driving shaft in a substantially vertical position, a shaft coupled to the motor shaft and rising within the aforesaid casing, a pinion connected to the upper end of the last mentioned shaft, a gear wherewith said pinion meshes, a flexible shaft having one of its ends rotatably supported within the bottom of the casing in a substantially vertical position and to which said gear is secured, the flexible shaft depending from the casing and capable of free swinging movement, and a manicuring instrument carried by the free end of the flexible shaft.

6. In a manicuring device of the class set forth, the combination of a structure incorporating a hollow base, a bracket rising from the base and offset laterally with respect thereto, and a gear case carried by the upper end of the bracket and overhanging the base, a motor supported within the base with its shaft in a substantially vertical position, the base and said casing having hollow bosses that are in substantially vertical alignment, a sleeve supported by and between said bosses, a shaft coupled to the motor shaft and rising through said sleeve, a pinion within the gear case connected to the last mentioned shaft, a flexible shaft having one of its ends extending through and rotatably supported by the bottom wall of the gear casing, a gear secured to said flexible shaft and meshing with the aforesaid pinion, said end of the flexible shaft being substantially parallel to the second mentioned shaft and located beyond the side thereof remote from the before mentioned bracket, said flexible shaft depending from the gear casing for free swinging movement, and a manicuring instrument carried by the free end of the flexible shaft.

7. In a manicuring device of the class set forth, the combination of a structure incorporating a hollow base, a bracket rising from

and offset to one side of the base, and an open top casing supported by the bracket and overhanging the base, an electric motor mounted in the base, an electric switch supported by the base for controlling said motor, power transmitting mechanism within the aforesaid casing, driving connections between the motor and said mechanism, a flexible shaft operatively connected to said mechanism and depending from the casing and capable of free swinging movement, and a manicuring instrument carried by the free end of the flexible shaft.

8. In a manicuring device of the class set forth, the combination of a structure incorporating a hollow base, a bracket rising from and offset to one side of the base, and an open top casing supported by the bracket and overhanging the base, an electric motor mounted in the base, power transmitting mechanism within the aforesaid casing, driving connections between the motor and said mechanism, a flexible shaft operatively connected to said mechanism and depending from the casing and capable of free swinging movement, a manicuring instrument carried by the free end of the flexible shaft, and a cover for the casing.

9. A manicuring device comprising a supporting member, a mandrel rotatably mounted therein, a slide reciprocably supported by the member for movement transversely of the mandrel, the mandrel being provided with an eccentric portion having driving connection with the slide, and a manicuring tool carried by the slide.

10. A manicuring device comprising a supporting member, a mandrel rotatably mounted therein, a slide reciprocably supported by the member for movement transversely of the axis of the mandrel, the slide having a groove that is arranged substantially at right angles to the direction of movement of the slide, a pin carried by the mandrel and eccentric with respect to the axis thereof, said pin operating within the groove of the slide, and a manicuring tool carried by the slide.

11. A manicuring device comprising a handle having a longitudinal bore and a guide-way extending transversely of said bore and opening through the front of the handle, a mandrel journaled within said bore, a crank pin carried by the forward end of the mandrel, a slide reciprocable within the guide-way, said slide having a groove at substantially right angles to its direction of movement, said crank operating within said groove, and means for attaching a manicuring tool to the slide.

12. A manicuring device comprising a handle having a longitudinal bore and a guide-way extending transversely of and opening through the forward end of the handle and into which said bore opens, a mandrel journaled within said bore and having a crank pin

that projects into the guideway, a slide reciprocable within the guideway and having a groove in its rear face that is at substantially right angles to the direction of movement of the slide, a block slidable in said groove and having a bearing aperture within which said crank pin is journaled, and a manicuring tool carried by the slide.

In testimony whereof, I hereunto affix my signature.

AUGUST E. R. BLOMQUIST.
